MACHINE FOR MAKING PULP ARTICLES

Edward M. Paterson, Whittier, and Ray O. Wilson,
Los Angeles, Calif., assignors to Plastic Fibre
Corp., a corporation of California

Application December 28, 1936, Serial No. 117,804

1 Claim. (Cl. 92—59)

This invention relates to the manufacture of articles from paper pulp and the like and more particularly to methods of and machines for molding articles from thin wet pulp material in a single operation.

An object of the invention is to produce relatively thin molded pulp articles in which the pulp fibers are so interlaced and extended in various directions as to provide maximum strength in the finished article.

A more specific object is to provide a porous mold or die for simultaneously shaping thin articles from a mixture of pulp suspended in liquid and squeezing out the excess liquid, in which the liquid is discharged from the mold in such a way as to leave the pulp fibers in the finished article in such positions as will impart maximum strength to the article against cleavage in response to bending strains.

Another object is to provide an automatic machine comprising separable molds or dies capable of operating continuously to receive pulp material and discharge pressed pulp articles at definite intervals.

Various more specific objects, and features of the invention, will become apparent from the detailed description to follow of a machine in accordance with the invention for making pulp coat hangers.

In accordance with the present invention, we produce thin pressed pulp articles of uniform substantial strength throughout by staggering all the discharge pores in each die face with respect to the pores in the other die face.

The invention will now be explained by describing in detail a complete machine for pressing pulp coat hangers, it being understood that various departures can be made from the particular structure shown without departing from the invention.

In the drawings:

Fig. 1 is a side elevation of a complete pulp press in accordance with the invention;

Fig. 2 is a sectional view of the machine, the section being taken substantially along the line II—II in Fig. 1;

Fig. 3 is a detail section through the pulp reservoir of the machine, the view being taken along the line III—III in Fig. 2;

Fig. 4 is a detail longitudinal vertical section taken through the center of the mold;

Fig. 5 is a fragmentary plan view, partly in section, of a part of the mold and its actuating mechanism;

Fig. 6 is a detail transverse section through

the mold, the section being taken along the line VI—VI of Fig. 5;

Fig. 7 is a detail cross section taken through a portion of one of the plunger dies, the section being taken along the line VII—VII in Fig. 6 with member 16 omitted;

Fig. 8 is a rear view of one of the forms and plungers of the press showing certain elements in section, the view being taken looking in the direction of the arrows in Fig. 5;

Figs. 9, 10, 11, 12 and 13 are schematic views showing the elements of the press in successively different positions of operation.

Fig. 14 is a detail section taken through one of the plunger dies parallel to and adjacent the end 15 of the plunger, the section line being indicated at XIV—XIV in Fig. 13.

Fig. 15 is a greatly enlarged detail longitudinal section through the ends of two juxtaposed plungers showing the disposition of the apertures 20 therein, the section being taken in the plane XV—XV of Fig. 14.

Fig. 16 is an elevation view of a completed coat hanger made in accordance with the invention.

Fig. 17 is a detail cross section through a portion of the coat hanger, the section being taken in the plane XVII—XVII of Fig. 16.

The particular machine disclosed in the drawings is intended for the manufacture of coat hangers, such as shown in Fig. 16, from paper 30 pulp or other fibrous plastic material.

Hangers of this type comprise an upper curved bar 1 connected at its outer extremities to the extremities of a straight lower bar 2 which serves to reinforce the upper bar 1 and also function 35 as a support over which the trousers of a suit of clothes may be hung. The hanger is provided with a hook 3 made of wire and having a straight lower section terminating in an enlarged head 4 which is embedded in the upper bar 1. The head 4 prevents the hook 3 from pulling out of the bar, although by virtue of the fact that the wire and the head embedded in the bar are round, the hook may be rotated. Hangers of the type illustrated in Figs. 16 and 17 may be molded 40 complete in one operation from a mixture of pulp suspended in water in the machine now to be described.

Referring first to Figs. 1 and 4, our machine comprises a sturdy supporting frame 10 of cast 50 iron or other suitable material on which the various moving parts of the machine are supported in proper relative positions. The mold or die proper consists of a pair of generally similar side forms 11 and 12, respectively, which define pas-

sages having the same cross sectional dimensions as the hanger to be manufactured, and a pair of similar plungers 13 and 14, respectively, which fit within the side forms 11 and 12, respectively, and seal therewith.

The ends of the plungers 13 and 14 compress the fiber mixture within the forms 11 and 12 and the ends of the plungers in contact with the pulp define the shape of the opposite faces of the finished hanger. As shown to best advantage in Fig. 4, the form 11 is provided with a core 15 and the form 12 is provided with a core 16, which cores define the openings in the finished hangers. The cores 15 and 16 are rigidly attached to the forms 11 and 12, respectively, by base plates 17 and 18, respectively. The inner ends of the forms 11 and 12, and their cores 15 and 16, are ground square and smooth to define contact faces which, when the two forms are pressed together, meet to form a substantially fluid-tight joint. To reduce the possibility of foreign matter lodging between the contact faces of the forms, the outer edges of the formed ends are preferably beveled as indicated at 19, thereby reducing the width of the ground faces which contact each other. The faces of the two forms are slightly recessed to permit entry therebetween of the hook 3 of a hanger to be molded, and a notched guide plate 20 is preferably provided on top of the form 11 to aid the operator in aligning the hook 3 when the latter is inserted between the forms.

The forms 11 and 12 are slidably supported for movement toward and away from each other by a pair of slide bars 22 and 23, respectively, which extend longitudinally across the machine and are supported at opposite ends in brackets 24 attached to the frame 10. The bars 22 and 23 are positioned slightly above the main portions of the forms 11 and 12 adjacent the side edges of the latter, and brackets 25 and 26 having eyes therethrough for receiving the bars 22 and 23, respectively, are formed integral with the forms. By means of the mounting described, the forms 11 and 12 are positively supported for free longitudinal motion along the bars. The plungers 13 and 14 are slidably supported in turn by the forms 11 and 12, in which they are slidily fitted.

In the operation of the machine the forms 11 and 12 and the plungers 13 and 14 are reciprocated through definite paths to receive a charge of pulp, compress it into a hanger, discharge the hanger, and then repeat the cycle.

To move the forms and plungers the proper distances in the proper sequence, a cam driving mechanism is employed. This cam mechanism comprises a main cam shaft 27 which extends transversely of the machine below the forms 11 and 12 and is journaled in bearings 28 and 29 in the frame 10.

The shaft 27 has a worm gear 30 keyed to one end thereof as shown in Fig. 2, which worm gear functions to drive the shaft 27 and is in turn driven by a worm 31 on a drive shaft which may in turn be rotated from any suitable source of power.

Keyed to the cam shaft 27 between the bearings 28 and 29 are three cams 32, 33 and 34. Each of the cams 32 and 34 has a single cam face cooperating with cam followers 37 (Fig. 1) and 38 (Fig. 2), respectively, which followers are linked to the forms 12 and 11, respectively. The central cam 33 has two identical cam faces operating with cam followers 39 and 40, respec-

tively, which are linked to the plungers 14 and 13, respectively.

The linkage for coupling the cam follower 38 to the form 11 comprises a yoke 41 to which the follower 38 is rotatably secured and which yoke 5 is slidably supported for horizontal movement by a bushing 42 having parallel upper and lower faces which slidably engage the yoke 41. The bushing 42 is drilled to receive the shaft 27 upon which it floats between the cams 34 and 33. 10 The yoke 41 is pivotally connected by a rod 43 to the lower end of a lever 44 fulcrumed on a stationary shaft 45 supported on the frame 10. The upper end of the lever 44 is connected by a yieldable link 46 to a bracket 47 projecting from the 15 plate 17 which, as previously described, is anchored to the form 11.

The flexible link 46 consists of a pair of levers 48 and 49, respectively, which bear against and fulcrum on a pin 50 positioned therebetween. 20 The lower end of the lever 48 is pivotally connected by a pin 51 to the upper end of the lever 44 and the lower end of the lever 49 is pivotally connected by a pin 52 to the bracket 47. Compressive strains applied to the lower ends of the 25 levers 48 and 49 tend to separate the upper ends of the levers. Such separation is resiliently resisted by a helical spring 53 surrounding a bolt 54 which extends through eyes provided therefor in the upper ends of levers 48 and 49. The bolt 54 has a head 55 on one end which bears against the lever 49 and a nut 56 is provided on the other end of the bolt for compressing the spring 53 between the nut and the upper end of the lever 48. 30 The upper ends of the levers 48 and 49 are preferably made substantially longer than the lower ends so that a substantial amplification of force may be obtained and the necessary spring force supplied by a relatively light spring. 35

The link mechanism for connecting the cam 40 follower 37 to the form 12 is substantially identical with that described for connecting the cam follower 38 with the form 11; thus it consists of a yoke 41', bushing 42' (floating on the shaft 27 between the cams 32 and 36), rod 43', lever 44', 45 and yieldable link 46'. The construction of the yieldable link 46' is identical with that of the link 46 and need not be described in detail.

The cams 32 and 34 function to move the cam 50 followers 37 and 38 outwardly to positively force the forms 11 and 12 together. To retract the forms and cause the followers to remain in contact with their associated cams, a helical tension spring 57 is connected at opposite ends to the 55 lower ends of the levers 44 and 44'.

The cam followers 39 and 40, cooperating with the cam 33 for actuating the plungers 14 and 13, respectively, are connected to their associated plungers by lever and toggle mechanisms. Thus 60 the follower 40 is rotatably mounted on the inner end of a lever 58 which is fulcrumed near its center on a stationary shaft 59 supported in the frame 10, and the outer end of lever 58 is pivotally connected to the lower end of a yieldable 65 connecting rod 60. The yieldable connecting rod 60 is identical with a corresponding rod 60' associated with the cam follower 39, and since the latter is shown in section in Fig. 4, the construction will be described with reference to the rod 70 60'. Thus the yieldable connecting rod 60' comprises a lower rod 61 having a nut 62 on its upper end which supports a washer 63 bearing against the lower end of a helical compression spring 64. The upper end of spring 64 bears against a flange 75

65 on a socket member 66 which is screwed onto the lower end of an upper rod 67.

5 A pin 68 of reduced diameter extends from the upper end of the lower rod 61, passing through bushing 69 screwed into the lower end of the socket member 66. Pin 68 has a head 70 on its upper end which is reciprocal through a short distance within the socket member 66. When no compressive force is applied to the rod 10 60, the rods 61 and 67 are in separated positions as shown in Fig. 4, but when the compressive force applied to the rod 60 exceeds a predetermined value, the spring 64 yields, permitting the pin 68 to slide into the socket 66.

15 The upper end of the rod 60 connects to a bearing member 71 which is rotatably mounted on a movable shaft 72 substantially at the center of the latter. Also rotatably mounted on the movable shaft 72 on opposite sides of the bearing member 71 (Fig. 5) are the bearing ends 73 of a pair of links 74 formed integrally with, and extending from, a sleeve 75 rotatably mounted on a shaft 76 supported in brackets 77 extending from the frame 10 of the machine. Rotatably 20 mounted on the outer ends of the movable shaft 72 are the bearing ends 78 of a pair of links 79, the inner ends of which terminate in bearing members 80 rotatably mounted on pins 81 supported in bifurcated brackets 82 secured to the 25 rear end of the plunger 14.

The plunger 13 is similarly connected to the upper end of the yieldable connecting rod 60' by members 71' and 82' inclusive.

In operation as the rotation of cam 33 forces 35 the cam followers 39 and 40 downwardly, the levers 58 and 58' are rotated to move the rods 60 and 60' upwardly, thereby moving the shafts 72 and 72' upwardly and moving the links 74 and 79, and 74' and 79' upwardly at their lower ends 40 to thereby shift the plungers 14 and 13, respectively, inwardly. As the shafts 72 and 72' approach the common plane of shafts 76 and shafts 81, the force on the plungers is greatly multiplied, which is highly desirable in view of 45 the increased resistance offered to the plungers by the pulp as it becomes more highly compressed.

To retract the plungers 13 and 14 and maintain the cams 39 and 40 in contact with the cam 50 33, tension springs 83 and 83' are connected between the outer ends of the levers 58 and 58', respectively, and stationary pins 84 and 85, respectively, anchored to the frame 10 of the machine.

55 The cams 32, 34 and 33 are so shaped as to provide a desired sequence of movements of the forms and the plungers. However, before describing this movement, certain auxiliary mechanisms will be described which function in synchronism with the particular sequence of form and plunger movement utilized.

Thus the compression chamber defined by the plungers and the forms must be filled with the pulp and water mixture during each cycle 65 of operation. To introduce a pulp and water mixture into the form, a port 90 is provided in the upper side of form 12, which port communicates through a manifold 89 consisting of a fitting 91 and a flexible hose connection 92 with 70 the lower end of a storage reservoir 93, which is also communicated through a manifold 94, extending from the upper side thereof with a main pulp tank 95 mounted on the top of the machine and constantly kept at least partially filled 75 with a dilute mixture of pulp and water. The

reservoir 93 (referring to Fig. 3) comprises a cylindrical container stationarily supported on the frame of the machine and having therewithin a sleeve valve 96 mounted on a shaft 97 which is journaled for rotation in the end walls of the 5 container 93 and extends therebeyond at one end and has keyed to that end a crank arm 98 which is connected by a rod 99 to a lever 100 which is mounted on the outer end of the stub shaft 59', which extends through the frame 10 on the exterior side thereof. This lever carries a cam roller 102 which bears against the under side of a cam 103 keyed to the outer end of the cam shaft 27. A tension spring 104 is connected between the extreme outer end of the lever 100 and the frame 15 of the machine at a point thereabove to retract the lever 100 and maintain the cam follower 102 against the cam 103.

The cam 103 periodically moves the lever 100 and the rod 99 from the normal position shown 20 in Fig. 1 and Fig. 3 through a distance sufficient to rotate the crank arm 98 through substantially 60°, retain it in that position for an interval, and then release it, the spring 104 restoring the valve to the normal position. In the normal position as shown in Fig. 3, a port 105 in the valve sleeve 96 is in registration with the manifold 94 extending to the supply tank 95 so that under these conditions the reservoir 93 fills with a mixture of pulp and water from the tank 95. When 30 the crank 98 is rotated through substantially 60° as described, the port 105 first passes out of registration with the manifold 94 and thereafter a port 106 moves into registration with the manifold 89 leading to the form 12. However, the 35 port 106 does not begin to register with the manifold 89 until after the port 105 has moved completely out of registration with the manifold 94. While the port 106 is in registration with manifold 89, the pulp and water mixture in the reservoir 93 is discharged through the manifold 89 into the form 12. To facilitate rapid transfer of the tank contents into the form, compressed air is admitted through a pipe 107 into the upper part of the reservoir 93 (through the port 40 105 in the valve 96) as the port 106 reaches full registration in position with the manifold 89.

45 Thus the air line 107 is provided with a valve 108 therein (Fig. 1) which valve has an actuating handle 109 positioned in the path of a trip 50 110 clamped on the rod 99 so that as the rod completes its downward movement, the trip 110 bears against the handle 109 to open the valve 108. However, as soon as the rod 99 starts its return movement, the trip 110 leaves the handle 109 and the valve 108 automatically closes.

To prevent a hanger adhering to one or the other of the forms or plungers as the latter are retracted, we provide a means for engaging the hanger hook 3 and preventing longitudinal motion of the latter during retraction of the forms and plungers. This means consists of an arm 111 having a bifurcated downwardly depending tip on its outer end adapted, when the arm is in the position shown in Fig. 2, to enclose the curved part of the hanger hook 3. The arm 111 is keyed to a shaft 112 which extends longitudinally of the machine and is supported in bearing members 113 adjacent its ends. There is also keyed to the shaft 112 a short arm 114, the outer end of which is pivotally connected to the upper end of a rod 115 which is slidably supported adjacent its lower end in a stationary guide 116.

70 The extreme lower end of the rod 115 carries a pin 117 which extends into a slot 118 in one 75

end of a lever 119 which lever is fulcrumed on a stationary pin 120 secured to the frame of the machine and carries on its opposite end a cam follower 121 which bears against a cam 122 mounted on the main cam shaft 27 just behind the cam 103. The rod 115 is retracted and the cam follower 121 maintained against its associated cam by a helical spring 123 which surrounds the rod and is compressed between the guide 116 and a stop member 124 secured to the rod.

In accordance with the invention, hangers are pressed from a relatively thin water pulp mixture and the excess water is forced out of the material during the pressing operation. This water escapes through apertures provided therefor in the ends of the plungers 14 and 13. These apertures are indicated at 130 and 131 in the plungers 14 and 13, respectively, in Fig. 4. The apertures communicate at their rear ends with passages 132 and 133, respectively, formed in the respective plungers, which passages in turn communicate with elongated recesses 134 and 135 formed in the lower portions of the plungers adjacent the lower surfaces of the forms 12 and 11, respectively. The forms in turn have ports 136 and 137, respectively, communicating with the recesses 134 and 135, respectively. The ports 136 and 137 are connected by flexible hose connections 138 and 139, respectively, with a waste pipe 140 through which the excess water is discharged and used for preparing additional pulp mixture.

The construction of the main elements of the machine having now been described, the manner in which the different elements cooperate will now be explained by following through the normal operation of the machine.

Referring to Figs. 4 and 9, both of which views are taken with the machine in the same position, it will be observed that the faces of the plungers 13 and 14 are equally spaced from a central plane, which plane is indicated by the broken line 150. The plungers are in their extreme outmost positions as indicated by the fact that the cam followers 39 and 40 are resting on the lowermost part of cam 33. In this position also the forms 11 and 12 are in abutting relation, but their plane of intersection is positioned to the right of the center line 150, in which position the port 90 is uncovered by the plunger 14. In this position also the cam follower 102 is riding against the high part of cam 103, displacing the lever 100 and the rod 99 into lowermost position in which the valve 96 in the pulp reservoir 93 has disconnected the reservoir from the manifold 94 and has connected it to the manifold 89 for discharging pulp in the reservoir into the mold. In Fig. 9 the mold has been indicated as filled. The parts remain in the positions shown in Figs. 4 and 9 for only a short interval as by virtue of the air pressure delivered through pipe 107 to the reservoir 93, the pulp charge in the latter is delivered very quickly to the mold.

The rotation of the cam shaft 27 out of the position shown in Fig. 4 permits the cam follower 102 to be retracted by the spring 104 to restore the valve 96 to normal position so that it is again communicated with the main pulp tank 95 through manifold 94 and begins to fill with pulp. The cam followers 39 and 40 ride on a concentric portion of the cam 33 for a short interval, maintaining the plungers 13 and 14 in the same positions, but the cams 32 and 34 con-

trolling the forms 11 and 12 shift the latter in unison while still maintaining them in abutting relation so that they are moved into the position shown in Fig. 10 in which the juncture plane of the forms lies in the center plane 150 and the inlet port 90 in form 12 is carried past the end of the plunger 14, thereby closing the port.

During the preceding operations the arm 111 under the control of the cam follower 121 of the cam 122 was in elevated position clear of the coat hanger 3 as shown in Fig. 4. However, immediately following movement of the forms 11 and 12 to bring their juncture to the center line 150, the cam 122 shifts the arm 111 into lower position (shown in Fig. 2), in which the bifurcated tips of the arm straddle the hook 3 and remain in that position until the compression of the pulp has been completed and the forms and plungers separated.

The machine is now in condition to start the compression of the pulp in the mold and the cam 33 gradually forces the followers 39 and 40 downwardly to shift the connecting rods 60 and 60' upwardly thereby actuating the toggle links 74 and 79 and 74' and 79' to force the plungers 13 and 14 toward each other into the position shown in Fig. 11 in which the pulp is fully compressed. Of course as the pulp mixture in the mold is compressed, the excess water is discharged through the apertures 130, 131 in the plunger faces and through the passages 132, 133, the recesses 134 and 135 and the hose connections 138 and 139 to the waste water line 140. The pulp is compressed substantially to its limit of compressibility and during the final movement of the cam followers 39 and 40 and the levers 58 and 58', the springs 64 in the yieldable connecting rods 60 and 60' compress slightly to allow for slight variations in the thickness of the compressed hanger, which variations might be caused by employing pulp mixtures of slightly different concentration with respect to the amount of water present. If yieldable means were not provided somewhere in the linkage and excess fiber were introduced into the mold, terrific forces would be created that might wreck the machine.

Although it is not absolutely necessary to provide the spring links 46 between the forms 11 and 12 and their actuating levers, these links are highly desirable as they make it possible to operate the machine without having the parts adjusted with great precision. Thus it will be obvious that if the entire linkage between the cam followers 37 and 38 and their associated plungers were unyieldable, it would be necessary to adjust the machine very accurately to just bring the ends of the forms 11 and 12 together. If the adjustment were such as to tend to move the forms 11 and 12 toward each other, even to only a slight extent after they had come in contact breakage of some portion of the link train would result.

Following movements of the plungers into the innermost positions in which the pulp is fully compressed as shown in Fig. 11, continued movement of the cam shaft 27 and the cams thereon retracts the cam followers 37 and 38 to separate the forms 11 and 12 as shown in Fig. 12. Thereafter the continued movement of the cams retracts the followers 39 and 40 to separate the plungers 13 and 14, this movement continuing until the plungers are in fully separated position as shown in Fig. 13.

As was previously indicated, the arm 111 is engaging the sides of the hanger hook 3 during the opening of the forms and plungers (Figs. 12 and 13), so that despite any tendency of the compressed hanger to adhere to one or the other of the plunger faces, it is retained in central position by the arm 111 so that it is completely disengaged from the plungers and drops away from them out of the press. As the hanger drops out from between the plungers, it falls clear of the forms 11 and 12 onto a conveyer belt 155 supported upon pulleys 156 and 157 which travels continuously and carries the hanger out of the side of the machine where it is grasped by an operator and hung up to dry. An idler pulley 157' is provided to keep the under lap of the belt 155 clear of the worm wheel 30 and the belt is driven by pulley 157, which in turn is driven by a belt indicated at 158 from the main shaft of the worm 31.

As shown in Fig. 13, the plungers 13 and 14 are fully retracted and the forms 11 and 12 are also retracted equal distances on opposite sides of the center line 150. Continued rotation of the cams leaves the plungers in their spaced apart positions, the followers 39 and 40 riding on concentric portions of the cam 33 and the form 11 likewise remains in the position shown in Fig. 13 by virtue of the fact that its associated follower 38 is riding on a concentric portion of the cam 34.

However, during the final rotation of the cams from the position corresponding to the form position shown in Fig. 13 to the starting position shown in Fig. 9, the cam 37 rides onto a high part of its associated cam 32, thereby forcing the form 12 to the right past the center line 150 into engagement with the form 11 in which the inlet port 90 is again open and the cycle completed.

It will be observed that a complete cycle of operation is completed during each revolution of the cam shaft 27 and the various movements described are readily obtained by merely suitably shaping the various cams.

In Fig. 4, which shows the machine at the beginning of the cycle described, the yieldable link 46' is shown compressed, whereas link 46 is not compressed. The tension of the yieldable links 46 and 46' is so adjusted that slight differences in the frictional resistance encountered by the two forms 11 and 12 determine to a large extent which of the links 46 and 46' will yield. In the position shown in Fig. 4 the form 12 has just been moved to the right, whereas form 11 has not been moved to the left since it was retracted. Therefore the frictional resistance encountered by the form 12 in moving past the plunger 14 and also the frictional resistance between plunger 13 and form 11 tending to restrain the latter, link 46' yielded, whereas link 46 was displaced only slightly.

However, during the subsequent movement of the two forms to bring their juncture to the center line 150 (the position shown in Fig. 10), all of the moving force for moving both forms is applied through the link 46. Therefore, following movements of the forms into the center position shown in Fig. 10, the yieldable link 46 will have yielded to a greater extent than the link 46'.

A most important feature of construction in the present machine is the design of the plunger

faces which constitute the dies contacting and compressing the pulp. It has previously been indicated that these plunger faces are traversed by numerous apertures 131 and 132 in the respective dies for the discharge of excess water from the mold. It is not new broadly to provide apertures in the plungers for the discharge of the water, but we believe it to be new to so position the apertures in the two dies that all of the apertures in one die are in staggered relation with respect to the apertures in the other die. Thus, as shown in Fig. 14, the apertures 131 are staggered with respect to the apertures 130 and each aperture positioned substantially symmetrically equidistant from the group of nearest apertures in the other die.

The apertures 130 and 131 in the plunger faces are preferably positioned approximately $\frac{3}{8}$ of an inch apart and may be about $\frac{1}{2}$ of an inch in diameter. To prevent pulp being forced into the apertures and clogging them, and to prevent the loss of pulp from the mold, the apertured faces of the plungers are perfectly covered with a relatively dense wire screen as shown in Fig. 7. The screen 160 is drawn over the face of the plunger and retained in place by clamping strips 161 set in recesses provided therefor in the plunger edges and clamped in place by screws 162.

We have found it desirable in constructing pulp coat hangers to make the main cross members of the hangers in substantially I-beam cross-sectional shape as shown in Fig. 17. To this end the faces of the plungers 13 and 14 are slightly grooved or dished as indicated at 166 in Fig. 7. Coat hangers of I-beam cross section as shown in Fig. 17 have smoothly rounded edges which are more desirable than squared edges and also have greater strength than they would have if made of rectangular cross section because of the extra material at the upper and lower edges where tensile and compressive stresses are greatest.

It is to be understood that although the invention has been explained by describing in detail a specific pulp press for forming coat hangers, that various features of the invention are applicable for other purposes and may be employed not only in pulp presses for shaping other articles than coat hangers, but in presses for handling materials other than pulp. The invention is therefore to be limited only as set forth in the appended claim.

We claim:

A press for molding articles from fibrous pulp comprising: a pair of hollow forms mounted on supports for selective sliding movement and having cooperating faces, timed power means actuating the forms to move and hold them together with the faces engaging to effect a substantially fluid-tight seal and defining a pressing chamber, a plunger in each form having a substantially fluid-tight sliding fit therein, a port in the upper part of one of said forms for the introduction of pulp into the chamber, means shifting the forms while held together and while the plungers are stationary so that the port is closed by one of the plungers, and timed power elements actuating the plungers after the port is closed to shape and compress the pulp.
